FEEDING MECHANISM FOR TAPE APPLYING MACHINES

Robert A. Hartt, Lynn, Mass.

Application January 8, 1938, Serial No. 184,008

7 Claims. (Cl. 12—51)

It is a very common practice in the manufacture of shoes to apply a reinforcing tape to certain parts of the upper. Sometimes this is done in connection with the stitching of binding to an edge portion of the upper material. At other times the tape is applied independently. Such a tape is customarily coated with an adhesive which may be either of the normally tacky variety or of a thermo-plastic nature, and this adhesive is utilized in affixing the tape to the work even though the tape may also be stitched to the upper material, either simultaneously with its application, or in a subsequent operation.

It is the customary practice to supply tape of this character to the machine wound upon itself into the form of a roll. It is fed to the sewing or other tape applying instrumentalities solely by the work feeding mechanism. If the tape unwinds readily from the roll, no difficulty is encountered, but it is a very common experience for the tape to stick so firmly to the turn or convolution next below it, that it seriously interferes with its application to the upper material. Sometimes the required pull on the tape is so great that it distorts the leather, and even when this does not occur, the high resistance to the feeding movement of the tape slows up the operator and tends to produce flaws in the work.

The present invention deals especially with the conditions above described. It aims to devise a mechanism for feeding the tape to the stitching or other tape applying instrumentalities in such a manner that the difficulties above described will be eliminated, and the tape will be fed at the proper speed to suit the requirements of the machine.

The nature of the invention will be readily understood from the following description when read in connection with the accompanying drawings, and the novel features will be particularly pointed out in the appended claims.

In the drawings:

Figure 1 is a perspective view, somewhat diagrammatic in character, of a sewing machine equipped with a tape supplying mechanism embodying the present invention;

Fig. 2 is an end view on a larger scale of the more important parts of the mechanism shown in Fig. 1;

Fig. 3 is a sectional view showing the relationship between the feed roll and the tape supplying roll;

Fig. 4 is a sectional view on the line 4—4, Fig. 3; and

Fig. 5 is a side view showing a somewhat different mounting of the tape supplying roll.

Referring first to Figs. 1 and 2, the organization there shown comprises a sewing machine 2 of a common commercial type mounted on a bench 3. It is driven by an electric motor 4 through a mechanism commonly known as the "Singer transmission" and which comprises a counter shaft 5 located below the bench and extending parallel to it, this shaft being driven by a belt connection 6 with the motor 4. A loose pulley 7 on the shaft 5 is connected by a belt 8 to the pulley 10 on the machine, and the driving connection between the pulley 7 and the shaft 5 is controlled by a treadle 12 through the bell crank lever 13, these two elements being connected to each other by a link 14. The arrangement is such that normally the machine is idle even though the shaft 5 is continuously driven by the motor. When the operator depresses the treadle 12, however, it operates through the connections above described and through a friction clutch connection between the parts 7 and 9 to drive the former and thus to operate the sewing machine. In view of the fact that this mechanism is well known, no detailed description or illustration of it is believed to be necessary.

The particular arrangement illustrated is designed to stitch a binding B to one side of the work simultaneously with the sewing of the tape T to the opposite side of it. The binding comes down from overhead while the tape is fed from below, and the two meet just before the work is fed under the presser foot P of the machine.

The mechanism provided by this invention comprises a holder 15 for supporting a supply roll 16 of tape, and a feed roll 17 which withdraws or unwinds tape from the roll 16. In addition to the plate 15, the holder also includes another plate 18, Fig. 3, at the opposite side of the roll 16 from the plate 15, the two being secured together at the shank of the holder and also connected by a bolt 20 on which a spacing collar 21 is mounted. This bolt, together with the central core 22 serves to center the roll 16 of tape and to support it for free rotation around the core, the core holding the plate 15 and 18 spaced apart by a distance greater than the thickness of the supply roll 16, and these plates preventing the convolutions of the tape from slipping off the roll laterally. The holder is secured to a convenient support in any suitable manner as, for example, by the screws 23, Fig. 2. It should be noted that the spacing collar 21 is preferably made square in section, and that it slides in a

slot 24 in the holder, this slot being directed radially toward the axis of the feed roll 17. With this arrangement, and due to the manner in which the tape is drawn off the supply roll by the feed roll, these two rolls always remain in peripheral engagement with each other.

As best shown in Fig. 1, the feed roll 17 is mounted on a shaft 25 lying below the bench 3 and extending parallel to it. It is supported in 10 suitable bearings or hangers, and at its end opposite the feed roll it has a worm wheel 26 secured firmly thereto. This wheel is driven by a worm 27 mounted on a shaft 28 which is supported in bearings formed in a bracket 30 secured to the lower side of the bench. Mounted on this shaft 28 is a friction wheel 31 arranged to bear against the driven pulley 7 so that it is revolved by its frictional engagement with the member 7 whenever the latter is running. With this 15 arrangement the speed at which the feed roll 17 is driven will bear a definite and predetermined ratio to the speed of the tape applying instrumentalities and the ratio is made such that the feed roll withdraws tape from the supply roll 16 at exactly the rate at which the work is being 20 fed by the feeding mechanism of the sewing machine, although each has its own driving mechanism. The two are, however, maintained in synchronism by virtue of the fact that they 25 are both driven from a common driving element, namely, the pulley 7.

In the arrangement shown in Figs. 1 and 2, the supply roll 16 rests on the periphery of the feed roll 17, and the tape T is guided around approximately one-half the circumference of the feed roll and then is led upwardly through a slot 32 in the bench into position to travel forward over the surface of the feed plate of the machine to the needle and presser foot. Because of this arrangement the feed roll obtains a strong frictional grip on the tape and it exerts a prying force on the tape at the point where it leaves the roll. This arrangement thus exerts a substantially positive action on the tape to peel it off, or separate it from, the main body of tape on the supply roll. Simultaneously with the unwinding or pulling of the tape off the roll, it feeds it toward the sewing instrumentalities. As above indicated, the rate at which it is so advanced may be made exactly 40 that required by the speed of operation of the tape applying mechanism, notwithstanding variations in said speed. Also, because the supply roll 16 is always maintained in peripheral contact with the feed roll, the rate at which the latter feeds the tape is not affected by the reduction in diameter of the feed roll due to the withdrawal of tape from it. Preferably the feed roll is made of rubber or some other composition which will exert a strong frictional grip on the tape, and its surface may be notched, as shown at 33, Fig. 2, to increase such grip.

After the taping operation on a shoe upper or other article of work has been completed, the operator frequently draws a short section of tape 65 from the supply roll before cutting it off. In order to facilitate this operation, the feed roll preferably is mounted on the hub of a ratchet wheel 34, Figs. 3 and 4, loosely supported on the shaft 25. A spring pawl 35 mounted on a hub 36 which is secured fast to the shaft 25, drives the ratchet wheel and consequently the feed wheel 17 in a counter-clockwise direction, Fig. 2, when the shaft 25 is being revolved. However, if the operator pulls on the tape at a point after it has left the feed wheel, it will result in revolving said wheel 70

independently of its driving mechanism and thus permitting the operator to withdraw the desired length of tape.

It will be evident from the foregoing that the invention provides a relatively simple mechanism which serves to withdraw the tape positively from the supply roll and feed it positively toward the tape applying instrumentalities at just the rate required by them. The mechanism operates automatically and requires no attention on the 10 part of the operator. The fact that it feeds at the correct rate, avoiding either an excess or a deficiency in rate of delivery, is important since it avoids the presence either of any substantial slack or tension on the tape. The absence of drag 14 on the tape and pull on the work, as in prior arrangements, contributes to ease and speed of operation and to producing work of high quality. It is especially useful in those situations where an unusually sticky tape is required, since the tension necessary to unwind such a tape from the roll is, of course, much greater than with the more common forms of tapes. The fact, also, that the mechanism is easily applied to standard tape applying machines, is an important practical advantage.

In a sewing machine, such as that shown, the work is fed step by step. The driving element of the machine, however, revolves continuously, and the tape feeding roll 17 is driven by it so that the 20 rate of feed of the tape is continuous and is not affected by the intermittent feed of the work. Nor is the operation of the sewing mechanism affected adversely by the continuous feed of the tape so long as the tape is free from tension. If 25 the tape feed should be set for a slightly higher rate than that at which the sewing mechanism takes it, no substantial amount of slack would accumulate because any appreciable degree of slack will so reduce the grip of the roll 17 on the 30 tape as to slow down or perhaps momentarily stop the feeding of the tape. In other words, the pulling of the tape from the supply roll 16 by the feed roll 17 is largely dependent upon the grip exerted on the tape by the wrapping of the latter 35 around a relatively large part of the circumference of the feed roll, as above pointed out.

In the arrangement above described, the supply roll 16 always rests on the feed roll by gravity. Such a relationship, however, is not necessary, 40 and that shown in Fig. 5 often is preferred. Here the parts corresponding to those above described have been designated by the same, but primed, numerals. It will be observed that the slot 24', in which the centering bolt 28' runs, is inclined 45 upwardly. The action of the feed roll 17, however, in unwinding tape from the periphery of the supply roll, draws the roll itself up to the feed roll and always maintains it in contact therewith, this action being caused by the adhesion 50 of adjoining turns or convolutions of tape to each other.

While I have herein shown and described a typical embodiment of my invention, it will be understood that the invention may be embodied 55 in other forms without departing from the spirit or scope thereof. For example, the speed reduction mechanism through which the feed roll is driven from the power element that drives the tape applying machine may take a variety of 60 forms. In this arrangement, also, the bracket 30 is mounted for adjustment to vary the pressure 65 of the friction wheel 31 against the pulley 7, but a spring actuated arrangement for effecting this 70 adjustment is sometimes preferred. In some 75

cases, also, provision is made for adjusting the radial distance of the roll 31 from the axis of the pulley 7 to change the speed ratio between the latter member and the feed roll. These and other variations may be made without departing from the essential features of the invention. Also, that while the particular material handled by it has been referred to as "reinforcing tape" and the work as "shoe uppers", the invention is not limited in its usefulness to these precise materials, and that these terms, therefore, should be understood to include tape-like materials which the apparatus is capable of handling and articles of work other than shoe uppers to which the tape can be applied in essentially the manner above described.

Having thus described my invention, what I desire to claim as new is:

1. In a machine for applying reinforcing tape to parts of shoe uppers, the combination with tape applying instrumentalities, of means for supplying said tape to said instrumentalities comprising means for supporting a supply roll of said tape, a feed roll positioned immediately beside and in contact with said supply roll and around which the tape is drawn from the latter roll so that the rotation of the feed roll prys the tape off the supply roll, means for guiding the tape from said feed roll to said instrumentalities, and mechanism for driving said feed roll in a predetermined speed relationship to the operation of said applying machine, said guiding means, said feed roll and the means for supporting said supply roll being constructed and arranged to cause the supply roll to remain constantly in peripheral engagement with said feed roll notwithstanding the reduction in its diameter due to the withdrawal of tape therefrom.

2. In a machine for applying reinforcing tape to parts of shoe uppers, the combination with tape applying instrumentalities, of means for supplying said tape to said instrumentalities comprising means for supporting a supply roll of said tape, a feed roll positioned beside and in contact with said supply roll and around which the tape is drawn from the latter roll, means for guiding the tape from said feed roll to said instrumentalities, and mechanism for driving said feed roll continuously during the operation of the machine and in a predetermined speed relationship to the operation of said applying machine; said guiding means, said feed roll, and said means for supporting said supply roll being constructed and arranged to draw the tape around and in contact with a sufficient part of the circumference of said feed roll to enable the latter roll to pry the tape away from the supply roll even when it adheres firmly to the main body of tape on the latter roll.

3. In a machine for applying reinforcing tape to parts of shoe uppers, the combination with tape applying instrumentalities, of means for supplying said tape to said instrumentalities comprising means for supporting a supply roll of said tape, a feed roll positioned beside said supply roll and around which the tape is drawn from the latter roll, means for guiding the tape from said feed roll to said instrumentalities, a main driving element for said machine, and a reduction gear mechanism driven by said element and driving said feed roll continuously during the operation of

the machine and in a predetermined speed relationship to the operation of said instrumentalities.

4. In a combination according to preceding claim 1, the provision of connections between said feed roll and its driving mechanism for enabling the roll to be revolved independently of its driving means by a pull exerted on the tape after it has left the feed roll.

5. In a machine for applying reinforcing tape to parts of shoe uppers, the combination with tape applying instrumentalities, of a tape feeding roll, means for supporting a supply roll of tape for rotation in peripheral contact with said feed roll, devices for guiding the tape away from said feed roll and to said instrumentalities in such a direction that the tape is continuously wrapped around a large part of the circumference of the feed roll, said means supporting said supply roll for movement toward the feed roll to maintain it constantly in peripheral engagement therewith notwithstanding the reduction in the diameter of the supply roll as the tape is withdrawn therefrom, and mechanism for driving said feed roll continuously during the operation of said applying machine and in a predetermined relationship to such operation.

6. In a machine for applying reinforcing tape to parts of shoe uppers, the combination with tape applying instrumentalities, of a tape feeding roll, means for supporting a supply roll of tape for rotation in peripheral contact with said feed roll, devices for guiding the tape away from said feed roll and to said instrumentalities in such a direction that the tape is wrapped around a large part of the circumference of the feed roll, said means supporting said supply roll for movement toward the feed roll to maintain it constantly in peripheral engagement therewith notwithstanding the reduction in the diameter of the supply roll as the tape is withdrawn therefrom, a transmission mechanism under the control of the operator for driving said machine, said mechanism including a pulley, and connections between said feed roll and said pulley for driving the feed roll from the pulley, said connections including a friction wheel in contact with and driven by the pulley.

7. In a machine for applying reinforcing tape to parts of shoe uppers, the combination with tape applying instrumentalities, of a tape feeding roll, means for supporting a supply roll of tape for rotation in peripheral contact with said feed roll, devices for guiding the tape away from said feed roll and to said instrumentalities in such a direction that the tape is wrapped around a large part of the circumference of the feed roll, said means supporting said supply roll for movement into contact with the feed roll due to the pull exerted by the latter on the tape to maintain the two rolls constantly in peripheral engagement with each other notwithstanding the reduction in the diameter of the supply roll as the tape is withdrawn therefrom, means including transmission mechanism for driving said applying machine, manually operable means for controlling the application of power therefrom to said machine, and mechanism controlled by said manually operable means for driving said feed roll.

ROBERT A. HARTT.
